UNITED STATES PATENT OFFICE

SYDNEY SCHISHKA, OF LONDON, ENGLAND

DESIGN FOR A POCKET CASE FOR A TOBACCO PIPE AND ACCESSORIES

Application filed January 23, 1931, Serial No. 38,420, and in Great Britain June 24, 1930. Term of patent 7 years.

To all whom it may concern:

Be it known that I, SYDNEY SCHISHKA, a subject of the King of Great Britain, residing at Farringdon House, 29 Farringdon Street, London, E. C. 4, England, have invented a new, original, and ornamental Design for a Pocket Case for a Tobacco Pipe and Accessories, of which the following is a specification, reference being had to the accompanying drawing, forming part thereof.

case adapted to contain a tobacco pipe and accessories, the case being shown open, and

Figure 2 is a perspective view from a view point opposite to that shown in Figure 1 of the pocket case when closed about a tobacco pipe. The said figures of the drawings show my new design.

I claim:

The ornamental design for a pocket case for a tobacco pipe and accessories, as shown.

SYDNEY SCHISHKA.
